No. 726,784.

PATENTED APR. 28. 1903.

W. P. TIBBITS.

LIFE PRESERVER AND SWIMMING APPARATUS.

APPLICATION FILED JUNE 13, 1902.

NO MODEL.

UNITED STATES PATENT OFFICE.

WILEY PRESTON TIBBITS, OF TOLEDO, OHIO.

LIFE-PRESERVER AND SWIMMING APPARATUS.

SPECIFICATION forming part of Letters Patent No. 726,784, dated April 28, 1903.

Application filed June 13, 1902. Serial No. 111,506. (No model.)

To all whom it may concern:

Be it known that I, WILEY PRESTON TIBBITS, a citizen of the United States, residing at Toledo, in the county of Lucas and State 5 of Ohio, have invented certain new and useful Improvements in a Combined Life-Preserver and Swimming Apparatus; and I do declare the following to be a full, clear, and exact description of the invention.

10 The invention relates to life-preservers and swimming apparatus.

The object of the invention is to provide a device of this character which shall be simple of construction, comparatively inexpensive 15 of production, light in weight, and of so little bulk about the body when inflated ready for use that it can be conveniently worn at all times while on the water to prevent a person from drowning if thrown suddenly and without warning into the water from any cause whatever and which may also be used to good 20 advantage by persons learning to swim, it being absolutely impossible for a person to sink.

25 With these and other objects in view the invention consists of certain novel features of construction, combination, and arrangement of parts, which will be hereinafter more fully described, and particularly pointed out 30 in the appended claims.

35 In the accompanying drawings, Figure 1 is a view illustrating the application of the invention. Fig. 2 is a vertical sectional view through the life-preserver. Fig. 3 is a detail view of an air-valve which may be used in connection with the mouthpiece.

Referring to the drawings, 1 denotes the shoulder-support of my life-preserver, which may be in the form of a garment provided 40 with armholes 2 and a neckband 3, the latter of which is divided at front and rear and provided with buttons and buttonholes for fastening the garment around the neck after the head has been slipped through it. Any other 45 form of garment, harness, or attaching device may, however, be substituted for that described without departing from the scope or sacrificing any of the privileges of the invention.

50 The body portion of the life-preserver consists of a casing, within which is a spirally-arranged inflatable air-tight tube 4, pro-

vided at one end with a mouthpiece 5, adapted to be closed by a screw-cap 6, which is flexibly connected to the garment by a tape 55 or string 7, as shown in Fig. 1 of the drawings, or the said mouthpiece may be closed by an automatically-closing valve, as shown in Fig. 3 of the drawings. The casing within which this tube is secured is made of canvas, muslin, or any other suitable flexible textile material and is preferably of the same form as the tube and acts as a protecting-envelop therefor. When made in the same form as the tube, it has, of course, the same spiral 65 and has its edges stitched or otherwise secured together, so as to make a complete surrounding body portion for the wearer. By making this envelop spiral in form tubes similar to those now used for the inner tubes 70 of pneumatic tires may be used in the manufacture of the life-preservers.

Another important feature of the invention resides in contracting or reducing in diameter the upper end of the envelop through 75 which the mouthpiece of the tube projects, or, in other words, forming it into a narrow neck 8. This will prevent the rubber tube from accidentally working or being drawn from out of its envelop when it is in an inflated condition; but when in its deflated condition the tube may be readily withdrawn from its envelop for the purpose of replacing it with a new one should the old one become damaged or unfit for use by hardening. 85

This device may be conveniently worn about the body of a person under or over his or her regular garments, and thus a person be prepared for any accidents upon the water. It is also especially adapted for use in 90 learning to swim, as it is absolutely impossible for a person to sink while the preserver is about the body and in inflated condition. It may also be worn by seafaring men—such as fisherman and life-saving crews—and will 95 not interfere when in position about the body with their movements in performing their occupations.

Instead of using a cap, as hereinbefore described, for closing the opening in the mouthpiece I may use an air-valve, as shown in Fig. 3 of the drawings, and consisting of a cylindrical metal casing 9, preferably of aluminium, and which may be corrugated or

roughened on its outer surface, so that it may be securely attached to the tube of the mouth-piece. The casing 9 is open at the top and closed at its lower end, said end being provided with two small holes 10 for the admission of air to the tubing. The casing 9 is divided midway its length by a partition 12, which is provided with a central orifice, through which is adapted to pass the stem 13 of a check-valve 14. 15 denotes a coil-spring arranged within the lower portion of the casing and confined between the valve 14 and the lower end of the casing, the tension of said spring being to normally force the valve against the partition 12 and close the opening therein. The stem 13 of the valve is adapted to protrude slightly beyond the open end of the cylinder, so that when placed in the mouth the said end will press against the teeth and open the valve to admit air being blown in, and is also used to open the valve to allow the air to escape from the tubes after using.

From the foregoing description, taken in connection with the accompanying drawings, it is thought that the construction, mode of operation, and advantages of the invention will be readily understood without requiring an extended explanation.

Various changes in the form, proportion, and details of construction may be made within the scope of the invention without departing from the spirit or sacrificing any of the advantages thereof.

Having thus described my invention, what I claim as new, and desire to secure by Letters Patent, is—

1. A life-preserver consisting of a shoulder-support and a body portion connected thereto in the form of a spiral envelop the edges of which are secured together to form an inclosing body portion to surround the body of the wearer and one end of which is provided with a reduced neck portion, an inflatable tube located within the spiral envelop and following its sinuous direction and having its upper end extending through the reduced neck portion of the envelop and provided with a mouthpiece, and a cap for closing the mouthpiece, substantially as specified.

2. A life-preserver consisting of a garment to fit the shoulders and the waist, the waist portion of the garment being in the form of a spiral envelop and connected to the shoulder portion and having one end thereof free and pendent and reduced, and an inflatable tube arranged within said envelop and having its end projecting from without the reduced portion of the envelop and provided with a cut-off valve.

In testimony whereof I have hereunto set my hand in presence of two subscribing witnesses.

WILEY PRESTON TIBBITS.
